J. DURAND

SELF LOCKING SNARE FOR WOLVES

Filed Jan. 24, 1927

FIG. 2.

JULES DURAND,

INVENTOR.

BY *Harold L. Shipman*
ATTORNEY.

Patented May 29, 1928.

1,671,414

UNITED STATES PATENT OFFICE.

JULES DURAND, OF ELKDALE, MANITOBA, CANADA.

SELF-LOCKING SNARE FOR WOLVES.

Application filed January 24, 1927. Serial No. 163,189.

This invention relates to snares and particularly for catching wolves, although I do not limit myself to this particular use.

The object of my invention is to provide a construction which will tightly engage around the animal and any pull of the animal when once snared will tend to tighten the grip of the snare around such animal.

10 A further object is to provide a simple construction having few parts, which will be easily set and the parts so arranged that there is little or no possibility of the same getting out of order.

15 A further object is to provide a snare wherein the reciprocated member is normally free to move on the main wire, but when engaged thereto will cause a tight binding grip which cannot be released by 20 the animal caught in the snare.

Other objects and advantages of my invention will become apparent ensuing a perusal of the following specification read in conjunction with the annexed drawings, 25 in which:

Figure 1 is a side plan view of the preferred embodiment of my invention.

Figure 2 is a section of an end view showing particularly the position of the engagement member.

Figure 3 is a side elevation of the engagement member in engaged position.

Figure 4 is a sectional view taken on the line 4—4 of Figure 3 and showing a modified form of my invention.

Figure 5 illustrates a modified form for holding the looped portion 6.

Like numerals of reference designate corresponding parts throughout the different views.

5 indicates a rope preferably of steel wire although for certain purposes other ropes may be found sufficient for the purpose for which they are designed. This rope has its inner end turned back and securely engaged to form a small loop 6. Reciprocally mounted on the rope 5 is a U-shape member 7. 8 is a locking member pivotally supported on the pin 9 carried by the U-shape member 7. The upper end of this locking member 8 is curved as at 10 and is provided with a ratchet face. The opposite end of the locking member 8 is provided with an annular opening 11 through which the loop 6 is engaged.

From the description so far given, it

will be noted that I provide a simple construction reciprocatorily mounted on the rope 5, whereby any pull of the large looped end of the rope 5 will cause the U-shape 60 member to slide in the direction of the arrow A. When this large loop at the end of the rope 5 tightens around the wolf or any other animal, the lower end of the locking member 8 will move in the direction of 65 the arrow B and will cause the curved ratchet end 10 to tightly engage the rope 5. As long as the large looped end of the rope 5 is held tightly by the animal, the ratchet end 10 cannot disengage from its gripped 70 position on the rope 5.

It might be found advantageous to provide a keeper which will allow the upper end of the locking member 8 to turn in the direction of the arrow A, but will not allow it to release. For this purpose, I have illustrated in Fig. 4 a modified form of my invention. 12 indicates a spring member having one end fixedly engaged to one side of the U-shape member 7. The opposite end of the spring 80 member 12 is provided with an inwardly bent end. This end extends through a slot 13, engaging the ratchet face 14 on the side of the locking member 8. With a keeper of this nature, it would eliminate the possible 85 chance of a branch or some similar obstacle from striking or holding against the lower end of the locking member 8 and disengaging its upper end from its gripping position on the rope 5. When the trapper desires to release the locking member 8, a knife or other similar article inserted under the spring 12 will easily release the same.

The foregoing specification and annexed drawings disclose what I consider to be the best way of carrying my invention into practice; but it is to be understood that my invention is not limited to the precise details shown, as it will be evident that these 90 may be varied to some extent without departing from the nature of my invention.

What I claim as new is:

1. A rope, one end of said rope being looped and securely fastened back upon itself, a member reciprocally mounted on said rope, a locking member carried by first said member, the outer end of said locking member being engaged in the looped end of said rope and the free end of said locking member adapted to cause a binding effect on said rope in first said member.

2. A rope, one end of said rope being looped and securely fastened back upon itself, a member reciprocally mounted on said rope, a locking member pivotally carried by first said member and the free end of said locking member being eccentric to said pivotal connection so as to cause a binding effect on said rope in first said member.

3. A rope, a member reciprocally mounted on said rope, a locking member carried by first said member, the outer end of said locking member being engaged in the end of said rope, the free end of said locking member adapted to cause a binding effect

of said rope in first said member and a keeper member adapted to prevent accidental release of said locking member when in gripping position.

4. A rope, a member reciprocally mounted on said rope, a locking member carried by first said member, the outer end of said locking member being engaged in the end of said rope, the free end of said locking member adapted to cause a binding effect of said rope in first said member.

25
In testimony whereof, I affix my signature.

JULES DURAND.
